UNITED STATES PATENT OFFICE.

WILLIAM R. GAITHER, OF CHICAGO, ILLINOIS.

CALCULATING-MACHINE.

No. 831,425.

Specification of Letters Patent.

Patented Sept. 18, 1906.

Application filed November 27, 1905. Serial No. 289,234.

To all whom it may concern:

Be it known that I, WILLIAM R. GAITHER, a citizen of the United States, residing at Chicago, in the county of Cook and State of Illinois, have invented a new and useful Improvement in Calculating-Machines, of which the following is a specification.

My invention relates to an improvement in the class of registering adding-machines in which figures are listed by printing in columns and added and the totals recorded on sheets of paper.

The general object of my invention is to adapt the carriages of such machines for time-keeping and pay-roll work, while as now constructed they are only adapted to work on a sheet of paper of moderate length for listing checks and similar temporary work, which only goes through the machine once and is taken out; and to this end I provide means for carrying a roll of paper from which to pay off as needed a sufficient length of web to accommodate as many entries as it is possible to require to be made lengthwise of the web and means for taking up the sheet as it is fed from the roll, thus enabling the pay-roll to remain in the machine from one pay-day to the other by adapting it to be reeled back on the supply-roll for each new or daily set of entries, for which the carriage is set, as usual, over one space to the left.

The more specific objects of my invention are to adapt such registering adding-machines to be used for posting daily hours, days, tonnage, mileage, or any basis that is used in the payment of employees and for other purposes where daily cumulative totals are desired and to further and at the same time make use of the adding mechanism of the machine to carry forward the daily cumulative totals, and as the result of the attainment of these two objects to avoid expensive and otherwise objectionable requirements incidental to the usual method of calculating wages due employees and which increase in proportion to the number of employees. In order to state clearly the requirements referred to, it is necessary to give herein a short synopsis of the method in common use for handling the pay-roll, which my invention is designed to improve by substituting machine-work for much that has hitherto been required to be performed by the hand and brain. The time or other basis of pay-

ment is credited daily to each employee, and the pay-roll is closed usually once or twice each month. It then becomes necessary to foot up the total time credited to each employee for the period covered to enable it to be multiplied by the rate of pay and extended into money. This adding is done along a horizontal line of figures and is a tedious operation, especially where fractions occur. It is usually required to be done hurriedly and is gone over by two persons or sets of persons and often rechecked a third time, and even then errors are made, which, however, may not be discovered for some time after the employee has been paid, thereby causing dissatisfaction in addition to the great amount of labor involved. Moreover, employees sometimes leave between pay-days, and when one so leaves his time must be figured up quickly and errors often occur in that way also. Ten days is the more usual time allowed for closing large pay-rolls, and a considerable portion of this time is devoted to adding up and going over the hour or other basis of payment extensions.

By means of my improvement I adapt the adding mechanism of any registering-machine to add each day's time to the accumulated total of the preceding days in the period by the same operation which credits the time, so that at the end of the pay-roll period or at any time between pay-roll periods the pay-roll will show the total due each employee and leave nothing remaining to be done but the extension into money, which is usually done with the aid of a suitable wage-table.

Incidents of the accomplishment of my aforesaid objects are expedition in enabling institutions employing labor to ascertain promptly the results of their operations for the previous month by avoiding the delay due to work on pay-roll closing, which must be performed before the accounts for the month can be closed, and rapidity of posting and totalizing, with the advantage of producing printed, and therefore easily-legible, figures instead of handwriting.

Having thus premised a general statement of the nature and object of my invention, I will proceed to a more detailed explanation of it by reference to the accompanying drawings, in which—

Figure 1 shows my improvement applied

to a well-known calculating-machine, represented in slightly-modified form as to the casing in side elevation, with the right-hand side presented to view and with a portion of the casing broken away to expose the printing devices within. Fig. 2 is a corresponding view of the left-hand side of the improved machine; Fig. 3, a view of the same in rear elevation, and Fig. 4 a plan view of a section 10 of a web of paper having its surface arranged to adapt it for use with my improvement and illustrating the manner in which my improvement enables the machine to be operated.

The calculating-machine shown in the 15 drawings and to which my improvement is applied for illustrating one connection in which it is adapted to be used forms the subject of Letters Patent of the United States No. 595,864, dated December 21, 1897; but 20 my improvement is susceptible of use with equal advantage on other constructions of calculating-machines employing a reciprocable carriage for the paper and which is operative to print on the paper and add figures 25 in columns and record the totals, so that it is not my intention to be understood as restricting my improvement to any particular construction of such a calculating-machine.

A is the casing of the machine containing 30 the operating mechanism, which it is unnecessary to illustrate or describe in detail, since it is the same as that of the calculating-machine well known upon the market as the "Burroughs registering accountant," manufactured in accordance with Letters Patent 35 granted to William S. Burroughs, the earliest of which are Nos. 388,116, 388,117, 388,118, and 388,119, dated August 21, 1888, and later ones, of which are No. 420,618, dated 40 February 4, 1899, and Nos. 504,963 and 505,078, dated September 12, 1893. Reference may be had to these patents for a detailed explanation of the operating mechanism of the machine.

45 B denotes the numbered keys of the machine arranged in a series of parallel rows in the top of the casing, there being nine keys in each row, as shown in Figs. 1 and 2, and there being usually nine rows of the keys. The 50 keys in each row are numbered consecutively from front to rear with the nine digits and the several rows of keys represent different denominations, the row upon the right representing units, the next to the left representing tens, and so on to the ninth or left-hand row, in which the keys represent millions.

C is the operating-lever of the machine, by 55 means of which after the proper keys B to represent the amount to be added and printed 60 have been operated the addition and printing are effected by pulling the lever forward to its limit of stroke and then releasing it to permit it to return to normal position, such return being effected by a suitable spring in the 65 machine.

So much of the printing mechanism as is necessary to an understanding of my invention is exposed to view by the broken-away portion of the casing in Fig. 1, where the series of type corresponding with the right-hand row of keys is shown. There are nine of such rows of type arranged side by side and close together, one row corresponding to and coöperating with each of the rows of keys B. The type in each row are arranged 70 in five pairs, as shown, each pair being carried by an independent type-bar or plunger D, the five plungers in each row being mounted upon and carried by a sector-plate E, which is hung at its extreme forward end 80 upon a transverse rod (not shown) extending across the upper central part of the machine. Each plunger D is provided with two pins a b, the former of which is normally seated in a notch in the edge of the sector-plate E and the latter of which projects through a slot in 85 said plate and serves to hold the plunger in position and guide it in its movement independently of the plate. The uppermost type in each row is a cipher, and the type below it 90 represent the nine digits in regular order from "1" to "9." A roller F constitutes the platen, with which the type coöperate, and an inking-ribbon G passes vertically between the roller and the type.

95 The foregoing explanation is sufficient for a general understanding of the operation of the machine independently of my invention, which operation is as follows: When any key B in a given row is depressed and the lever C then drawn forward to its limit of movement, the sector-plate E corresponding to such row of keys will be first swung upward until its type corresponding to the operated key is brought approximately to the printing-point in front of the center of the platen-roller, whereupon the plunger carrying such type is thrown rearward and presses the inking-ribbon G against the platen-roller F to print the number on such type upon paper 100 interposed between the roller F and ribbon G, after which upon the release of the lever C the parts all return to normal position.

105 At H in Fig. 1 is represented a special key, which is the repeating-key in the aforesaid machine, and at I in Fig. 2 is represented another special key, which is the totalizing-key of the machine.

110 My improvement, which relates particularly to the printing attachment on a calculating-machine of the character thus described, involves lengthening of the carriage-way and providing on the laterally-shiftable carriage to be movable with it a feed for the paper on which the work of the machine is 115 performed, consisting of a lower roller carrying the supply of the paper in a roll and an upper roller upon which to wind the web from the lower roll and from which to rewind the web on the lower roll as the action of the 120 machine.

machine in forming columns of figures proceeds. The printing attachment illustrated is, except as to the width of the carriage-frame and extent of travel of the carriage 5 and the means I have devised for accomplishing my aforesaid objects for performing the work of the machine on a continuous web of adequately wide paper, that shown and described in the aforesaid Letters Patent No. 10 595,864 with reference to the modified form provided in Figs. 10 and 11 of the drawings in said patent, to which reference may be had for a more detailed description, that hereinafter given being sufficient, however, to enable those skilled in the art to understand 15 my improvement.

On the back of the casing A, near its base, is provided a rigid bar J, longer than the width of the casing and projecting to an equal extent beyond each side thereof. On the ends of this bar, respectively, are the upwardly-projecting and outwardly-curved brackets K and K', which serve to support all the devices to be described and involving my improvement. Journaled at its ends in bearings 20 at the upper ends of the respective side frames K K' is a shaft L, on which is a feed-roller M, shown to be divided into a plurality of sections disposed at uniform intervals along the shaft. At its right-hand end, Figs. 2 and 3, the shaft L has fast upon it a ratchet N, with which co-operates a pawl O, carried by an arm P, loosely hung at its forward end upon said shaft beside the ratchet and having connected to its rear end the upper end of a link Q. 25 A rock-shaft S is journaled in the side frame K and has rigidly secured upon its extreme left-hand end a forwardly-extending arm R, to which is pivoted the lower end of the link Q, the rock-shaft being actuated by contact with it of a stud Y on a lever X, located within the machine. The arm R is provided with two holes a' b', connected by a slot c', and the lower end of the link Q carries a stud d', which fits in and co-operates with the holes a' 30 b' and may be shifted from one to the other. On the opposite end of the rock-shaft S is secured between its ends a forwardly-bent lever T. An arm T' on the rock-shaft has its lower end connected by a coiled spring U with the side frame K, while its upper end extends into the path of the stud Y on the lever X, which is so connected with the main operating-lever C, by means unnecessary to 35 illustrate or describe here that whenever the lever C is pulled forward to its limit of movement the upper end of the lever X will be thrown forward and engage the stud Y with the lever T to press it slightly rearward and 40 rock it against the stress of the spring U. When the link Q is engaged with the hole b' in the arm R, which hole is nearest the fulcrum of the arm or lever, a less throw will be imparted to the link and the pawl-carrier P 45 and pawl O than when the lower end of the

link is swung forward and its stud engaged with the hole a'. The adjustment of the parts is such that when so engaged with the hole b' the pawl O will slip backward over one tooth of the ratchet N and advance the latter 70 the space of one tooth at each operation of the lever C of the machine; while when the lower end of the link is swung forward with its stud engaged with the hole a' the pawl will be given twice the extent of throw at 75 each operation of the lever C and the feed-roller and paper therefore advanced twice as far as under the first-mentioned adjustment. By this means the machine may be adjusted to print the items close together in each column or farther apart, as may be desired. 80

Extending between the upper ends of the frame members K and K' is the carriage-track A', provided with a longitudinal guide-rib on its top, and a U-shaped bearing-bar A² is rigidly fastened at its ends to said frame members below the track. A³ is the carriage fitting and seated on said track to be moved lengthwise thereof and from the ends of which project horizontally-rearward arms g, each 90 having a reinforcing-webbed junction at its outer end with the center of a vertical bar h, carrying a bearing-roller h' at its lower end, at which it runs on the bar A², which thus supplements the carriage A³ in supporting the 95 weight of the paper and rollers therefor carried by the bars h. On the lower ends of the bars h, which, together with the arms g, form a supplemental frame, are provided bearings i', in which is journaled a roller i for the roll of 100 paper (not shown) to be used with the machine and from which the paper is fed, and similar bearings k' are provided on the upper ends of the arms h for journaling in them an upper take-up roller k for the web of paper. 105 The rollers i and k, which are thus journaled on a carrier rigidly connected with the carriage A³ to move with it, carry pulleys p p, at which they are connected to cause turning of one to turn the other by an endless belt q. 110

The platen is shown in the form of a roller F, which is preferably rubber-faced and bears upon the roller M when the parts are in operative position, as in Figs. 1, 2, and 3, and the web of paper is passed between them, so 115 that when the roller M is actuated at each operation of the machine, as described, the paper which passes, as indicated by the dotted line W, over the roller i, over a suitable guide K², supported on the carriage A³, like that shown 120 in said Letters Patent No. 595,864, but wider, thence about the roller F to the roller k, upon which it is wound, will be slightly advanced to bring a fresh surface to the printing-line. The roller F is journaled at its ends 125 in the forward ends of arms C', shown to be pivotally supported at their rear ends on lugs l, rising from the ends of the carriage, to enable the roller F to be raised from contact 130 with the feed-roller M when desired by a han-

idle m on an arm C' , although there is no need for such raising of the platen-roller to permit inspection of the work, for the back of the casing A is formed on an incline, as represented at V , to permit the operator to view the printing on the paper at all times from his position of operating the machine without raising the roller F .

At F' is shown a pressure-roller bearing upon the upper side of the platen-roller for causing the paper to pass smoothly about the latter. The spindle of the roller F' is mounted at its ends in the front ends of levers F^2 , pivoted to the arms C' and engaged at their rear ends by springs n , which serve to press the roller F' into contact with the roller F . The lever F^2 at the left-hand side of the machine is provided with three arms, the arm F^3 of which forms a handle by which the roller F' may be lifted out of contact with the platen-roller when desired.

The carriage A^3 is free to be slid longitudinally upon the bar A' , and to relieve the friction between the parts ball-bearings are interposed between them, as shown at e . The lateral movement of the carriage A^3 for the printing of different columns is accomplished through the medium of a handle A^4 , rising from the carriage, and during such lateral movements the platen-roller F is adapted to be raised, as it must be, by the means provided for the purpose according to the aforesaid Patent No. 595,864, and these movements of the carriage for printing the columns side by side on the web are step-by-step movements, as provided for in the said Letters Patent.

The web W , Fig. 4, to be used with my improvement is of materially greater width than that for which the machine of the aforesaid Patent No. 595,864 is adapted and should be prepared, like the section of the sheet illustrated, with horizontal lines, each line being used for noting the time of a different employee. Each employee may be designated by a different number at the beginning of a horizontal line, these designating-numbers being shown on the web as running consecutively from "1." At the head end of the web are provided in series the numbers from "1" to "6," inclusive, representing the working days of the week and spaced apart to adapt each number to head a column of figures, and beyond the series of day-designating numbers are provided, each for heading a different column, the consecutive words "Rate," "Amount," "Deduction," and "Amount."

To explain the operation of the machine provided with my improvement, explanation of the notation for one employee will suffice—say of the employee designated "1." On the first day of the week the machine has been caused to mark his time as "12," meaning

hours. On the second day this number began the second column and under it was printed "13," representing the number of hours worked the second day, which, added to the previous number, made the total of twenty-five hours, and this total was carried forward to head the column for the third day, on which twelve hours were credited to the employee, making a total of thirty-seven hours, and so on to the sixth day, showing the total number of hours credited to the respective employee to be seventy. With the rate per hour noted in the next succeeding column the amount due the particular employee may by multiplying it by seventy be readily inserted into the next succeeding column, and any deduction noted by the machine in the deduction-column may be as readily subtracted from the gross amount and the sum due the particular employee noted by suitably operating the machine in the final-amount column. Thus on any day the pay due an employee may be readily and accurately ascertained by inspecting the sheet W , forming the pay-roll, and figuring out the final amount, and on pay-day the pay-roll is easily, quickly, and accurately gotten ready for paying off the hands.

As the web W is paid off from the roller i by the feeding action of the roller M any slack in the web between the platen and the take-up roller k may be wound upon the latter by applying to its squared projecting end a suitable crank-handle o and properly turning the take-up roller. When the first day's notation of the employee's time has been printed on the web for the succeeding day, the carriage is shifted to bring the next column-forming space in line to be printed by the machine, and the handle o is applied to the squared end of the roller i for turning the latter to rewind upon it the web preparatory to noting in the second column in succession the respective employee's total time, including his time of the succeeding day, his time for the second day and his total time on that day being obtained by pulling the lever C . Preparatory to each rewinding of the web upon the roller i the roller F should be raised out of contact with the roller M . The operation for each succeeding day is the same as that for the second.

When a pay-roll is made up on the web W , it may be severed from the latter and taken out of the machine, and the end of the web from which the pay-roll was thus severed may then be adjusted in the machine and fastened to the upper roller k for a new pay-roll. The web illustrated is adapted for a weekly pay-roll; but it may be wide enough and arranged for fifteen days or thirty-one days.

Obviously the manner in which time or other cumulative totals are obtained may be

varied to suit different conditions. Thus, by way of examples, for street-railway trainmen and others whose time is kept in hours and minutes daily machines that add hours and minutes, or fractional machines, may be used and the extension into money made at the end of the period. Where the time is straight days, the amount per day may be registered, if desired, instead of the hours, or by the use of tables or a comptometer all time may be extended daily into money and posted in money values instead of days or hours, or where employees are paid by mileage or tonnage or by the piece or on any other basis which requires registry to them of daily cumulative credits for services performed. My improvement is adapted to be used. Moreover, it is adaptable for equally advantageous use for other purposes besides payment of labor where daily cumulative totals are desired, as in large business-houses, factories, railway-offices, &c., for daily sales, shipments, production, materials used, daily charges to accounts, and the like, the names or numbers of articles or accounts or other items being used in that case instead of the names of or numbers denoting employees.

The best general explanation I can give of the new use to which my improvement adapts the calculator to be put is to take the last day in a pay period, which is usually seven, fifteen, or thirty-one days. When commencing to post the last day's time before closing the pay-roll, I begin with employee No. 1 in the vertical column of that day. Either by glancing at the previous day's total for that employee, where it is in sight on the machine, or else by raising the carriage slightly to bring the work into view I ascertain his total preceding time or wages due in the period and print that in the column. Then from his time-card or other report I print under that total the time or money due for the last day and then take the total for the two items on the machine. By following this procedure throughout the period I have his total hours or other basis of payment, or if it is possible to post each day's wages in money his total wages due correctly footed when the last day is credited to him.

What I claim as new, and desire to secure by Letters Patent, is—

1. In a calculating-machine of the character described employing a printing attachment containing a laterally-shiftable carriage, and a platen and paper-feeding means, the combination with a carriage of a web-guide thereon, a roller-carrier rigidly connected with said carriage to move with it, and lower and upper web-carrying rollers journaled on said carrier and adapted for winding and unwinding a web extending from one to the other of said rollers between said platen and feeding means, for the purpose set forth.

2. In a calculating-machine of the character described employing a printing attachment containing a laterally-shiftable carriage and a platen and paper-feeding means, a frame for said carriage extending across the back of the machine-casing and projecting beyond the sides thereof, a track extending between the ends of said frame and on which the carriage is movably supported, a web-guide secured on the carriage to move with it, a roller-carrier rigidly connected with said carriage to move with it, and lower and upper web-carrying rollers journaled on said carrier and adapted for winding and unwinding a web extending from one to the other of said rollers between said platen and feeding means, for the purpose set forth.

3. In a calculating-machine of the character described employing a printing attachment containing a laterally-shiftable carriage, and a platen and paper-feeding means, a frame for said carriage extending across the back of the machine-casing and projecting beyond the sides thereof, a track extending between the ends of said frame and on which the carriage is movably supported, a web-guide secured on the carriage to move with it, a supplemental frame rigidly connected with said carriage to move with it, and lower and upper web-carrying rollers journaled on said supplemental frame and adapted for winding and unwinding a web extending from one to the other of said rollers between said platen and feeding means, for the purpose set forth.

4. In a calculating-machine of the character described employing a printing attachment containing a laterally-shiftable carriage and a platen and paper-feeding means, a frame for said carriage extending across the back of the machine-casing and projecting beyond the sides thereof, a track extending between the ends of said frame and on which the carriage is movably supported, a web-guide secured on the carriage to move with it, a supplemental frame rigidly connected with said carriage to move with it, a bearing on said casing on which the supplemental frame travels, and lower and upper web-carrying rollers journaled on said supplemental frame and adapted for winding and unwinding a web extending from one to the other of said rollers between said platen and feeding means, for the purpose set forth.

5. In a calculating-machine of the character described, employing a printing attachment containing a laterally-shiftable carriage and a platen and paper-feeding means, a frame for said carriage consisting of a bar extending across the back of the machine-casing and projecting beyond the ends thereof, and brackets projecting upward from the ends of said bar, a track supported at its ends on said bracket and on which the carriage is movably supported, a bearing-bar connect-

6
ing said brackets below the track, arms extending rearward from the carriage and carrying vertical bars provided at their lower ends with rollers riding on said bearing-bar and having lower and upper roller-bearings, and web-carrying rollers journaled in said roller-bearings and adapted for winding and

unwinding a web extending from one to the other of said rollers between said platen and feeding means, for the purpose set forth.

WILLIAM R. GAITHER.
